UNITED STATES PATENT OFFICE

143,769

DESIGN FOR A COMBINED FENCE TOOL AND STAPLE PULLER

Francis J. Stiefvater, Utica, N. Y., assignor to
Utica Drop Forge & Tool Corporation, a corpo-
ration of New York

Application March 26, 1945, Serial No. 118,724

Term of patent 14 years

(Cl. D54—13)

To all whom it may concern:

Be it known that I, Francis J. Stiefvater, a citizen of the United States, in the city of Utica, county of Oneida, and State of New York, have invented a new, original, and ornamental Design for a Combined Fence Tool and Staple Puller, of which the following is a specification, reference being had to the accompanying drawing, forming a part thereof.

Figure 1 is a side elevational view of a combined fence tool and staple puller showing my invention;

Figure 2 is a front view of the Figure 1 looking from left to right;

Figure 3 is a rear view of the Figure 1 looking from right to left;

Figure 4 is a top view of the Figure 1; and
Figure 5 is a cross-sectional view along the line
5—5 of the Figure 1.

I claim:

The ornamental design for a combined fence
tool and staple puller, substantially as shown.

FRANCIS J. STIEFVATER.
